ARTICLE HANDLING APPARATUS

Henry R. Gotthardt, Louisville, Ky., assignor to
 Logan Co. Inc., Louisville, Ky., a corporation of
 Kentucky

Application May 18, 1938, Serial No. 208,685

9 Claims. (Cl. 214—130)

This invention relates to article handling apparatus, and more particularly to an apparatus for handling and turning coiled strip steel and the like.

5 In my prior Patent No. 2,101,738, granted December 7, 1937, I have disclosed a coil handling apparatus particularly adapted for receiving coils of strip steel in a vertical position, turning the coils to a horizontal position and feeding them 10 into an uncoiler. The prior apparatus, generally speaking, comprises a pair of sections arranged approximately at right angles to each other with one section being adapted to receive an incoming coil. The two sections are mounted 15 for bodily swinging movement through approximately 90 degrees whereby a coil on the normally horizontal receiving section will be turned with the sections to be supported on the other or discharging section with the latter in approximately 20 a horizontal position. The discharging section is provided with a relatively movable portion adapted to be tilted to discharge a coil therefrom to be received in an uncoiler.

In certain instances it is highly desirable to 25 provide a coil handling mechanism of the general character referred to which is adapted to up-end or turn a coil in either direction. In other words, it is desirable in an apparatus of the general type shown in my prior patent to sometimes use the discharging section as the receiving section to 30 support a coil to be transferred to the other section, normally the receiving section, to be discharged therefrom. Moreover, in such particular installations it is customary when placing a coil on one of the sections to transfer it thereto substantially horizontally from a ram truck 35 whereas, in some cases, a coil is placed on the other section, when the latter is to be used as the receiving section, by means of a magnetic crane or the like. Accordingly it frequently 40 occurs that a coil will be placed on the latter section with considerable shock, resulting in damage to the apparatus.

It is an important object of the present invention 45 to provide improvements in my prior structure referred to whereby a coil may be received on either section and turned to a position supported on the other section to be discharged therefrom.

A further object is to provide an article handling apparatus of the character referred to 50 wherein one of the sections is provided with a portion relatively movable to assist in feeding an article into or from the apparatus as may be desired.

55 A further object is to provide such an apparatus wherein the relatively movable portion referred to is mounted to turn on a horizontal pivot to slope downwardly toward the other section, when the latter is in approximately vertical position, to assist in feeding an article to the appa-

ratus, or wherein the relatively movable section, under such conditions, may be turned to tilt downwardly away from the other section to assist in discharging an article from the apparatus by gravity.

5 A further object is to provide an auxiliary conveyor section, cooperating with said relatively movable section, to assist the latter in feeding an article to or from the apparatus.

A further object is to provide an auxiliary conveyor section having means associated therewith for causing it to assume a position inclined downwardly toward the article turning means to assist in feeding an article thereto, or downwardly away from the article turning means to assist in discharging an article therefrom, the conveyor section and the relatively movable section of the coil turning means being capable of assuming corresponding positions whereby each acts with the other in feeding an article to or from the apparatus.

A further object is to provide means for cushioning the auxiliary conveyor section to absorb shocks incident to the placing thereon of heavy articles such as coils of strip steel.

25 A further object is to provide means associated with the tilting means of the auxiliary conveyor for resiliently supporting one end of the latter to cushion shocks when heavy articles are placed on the auxiliary conveyor.

30 Other objects and advantages of the invention will become apparent during the course of the following description.

In the drawings I have shown one embodiment of the invention. In this showing:

35 Figure 1 is a side elevation of the apparatus,

Figure 2 is a plan view,

Figure 3 is a section on line 3—3 of Figure 1,

Figure 4 is a similar view on line 4—4 of Figure 1,

40 Figure 5 is a similar view on line 5—5 of Figure 1, and

Figure 6 is a horizontal sectional view on line 6—6 of Figure 1.

45 Referring to the drawings, the numeral 10 designates a pair of spaced parallel supporting frames suitably connected by end frame members 11. The side frame members support opposite bearings 12 in which are rotatably mounted axles or shafts 13 carrying flanged wheels 14 at 50 their ends. The wheels 14 at the right hand side of the apparatus as viewed in Figure 1 can be mounted on a common axle while the other pair of wheels 14 may be mounted on short shaft sections having their inner ends similarly mounted 55 in bearings 12 carried by supports 10'.

An article turning support indicated as a whole by the numeral 15 is adapted to be supported by the wheels 14 for the purpose of turning or up-ending articles to be handled by the 60

apparatus. The support 15 comprises a pair of arcuate side plates 16, each provided at its periphery with an arcuate rail member 17 secured thereto and engageable with the wheels 14. Accordingly it will be apparent that the support 15 as a whole is adapted to be turned to positions to be referred to and the turning movement takes place about a horizontal axis indicated in Figure 1 by the numeral 18, this point indicating the axis of the plates 16. The side plates 16 are connected and braced with respect to each other by transverse structural members 19 preferably of channel section.

The support 15 further comprises a pair of article handling and supporting sections indicated as a whole by the numerals 20 and 21 respectively, these article handling sections preferably being arranged approximately at 90 degrees to each other. It also will become apparent that these sections are arranged radially outwardly with respect to the center 18 so as to arrange the center of gravity of an article on the support reasonably close to the center 18. The plates 16 are cut back as at 22 and 23 and these edges of the plates are arranged approximately at right angles to each other and radially outwardly of the innermost portions of the sections 20 and 21 so as not to interfere with articles thereon.

The article handling section 20 comprises a pair of outer horizontal rail members 24 preferably of angle-section as shown in Figure 5 and the members 24 are connected by transverse braces 25. These braces carry a central rail member 26, parallel to the members 24. Conveyor rollers 27 are arranged between the rail member 26 and each of the rail members 24. The outer end of the section 20 carries a transverse shaft 28, such shaft being mounted in bearings 29 (Figure 5) secured to the rail members 24 and to a transverse brace 30 extending between the plates 16.

From the foregoing it will be apparent that while the section 20 is bodily movable with the support 15 when the latter turns on the axis 18 the section 20 is mounted to turn on the horizontal axis of the shaft 28 to assume positions inclined slightly downwardly or upwardly with respect to the horizontal when the support 15 is in the position shown in Figure 1. This change in angularity is provided in order to assist in moving articles to or from the support, depending upon whether the articles are being fed to the section 20 or are being discharged therefrom. For the purpose of determining the vertical position of the inner end of the section 20, when the support 15 is in the position shown in Figure 1, a transverse shaft 31 is mounted in bearings 32 supported on a transverse brace member 33 extending between and secured to the side plates 16. Inwardly of each bearing 32 the shaft 31 is provided with a cam 34 having high and low points 35 and 36. The shaft 31 may be turned by any suitable means such as a crank 37. When the support 15 and cams 34 are in the position shown in Figure 1, the section 20 will slope downwardly toward the left as viewed in Figure 1. If the crank 37 is rotated through 180 degrees, the inner end of the section 20 will be lowered to be supported on the low points 36 of the cams 34, in which case the section 20 will slope downwardly toward the right as viewed in Figure 1. In the former case, the section 20 acts as a gravity conveyor to tend to discharge articles from the support 15, and in the latter

case, the section 20 acts similarly to move articles into the support 15, and the reasons for this arrangement will become apparent.

The section 21 is similar to the section 20 in that it includes conveyor rolls. However, the 5 rolls 38 of the section 21 lie in a single plane since such section is particularly intended to support coiled sheet steel standing on end. The rollers of the section 21 are preferably troughed since the same type of coil is adapted to lie 10 thereagainst with its curved or cylindrical surface in engagement with the rollers of the section 21.

Therefore, the section 21 comprises a pair of series of conveyor rollers 38 inclined with respect 15 to each other in the manner shown in Figure 1 to form a troughed conveyor when the section 21 occupies the dotted line position shown at the right hand side of Figure 1. The inner ends of the rollers 38 are journaled in bearing brackets 20 39 (Figure 2) while the outer ends are journaled in side rails 40 preferably formed of angle section. In view of the fact that the outer ends of the rolls 38 are offset with respect to the inner ends, the angle sections 40 may be secured 25 to similar sections 41 supported by transverse braces 42 extending between the side plates 16 and to which the bearing brackets 39 are secured.

A pair of spaced angle iron brackets 42 are connected to each of the respective arcuately arranged braces 19 and a segment gear 43 is secured between the brackets of each pair 42, the teeth of this gear being concentric with the plates 16. This gear is used to deliver power to the support 15 to turn it between its two positions to be referred to. To furnish power for the turning movement of the support 15, a motor 44 (Figures 1 and 2) is mounted between the side frame members 10 and is provided with a drive shaft 45 coupled to the input shaft 46 of a conventional speed reduction gearing 47. The output shaft 48 of the gearing 47 is provided with a gear 49 meshing with the segment gear 43. Accordingly it will be apparent that the motor 44 may be driven in either direction to turn the support 15.

An auxiliary conveyor indicated as a whole by the numeral 50 is associated with the section 20 of the support 15. The conveyor 50 comprises side rails 51 and a center bearing bracket 52 and a plurality of rollers 53 is mounted between the bearing bracket 52 and each of the side rails 51. The rails 51 may be connected by cross members 54 to which the bearing bracket 52 is secured. The rollers 53 preferably correspond in arrangement to the rollers 27 and form therewith a continuous conveyor, as will become apparent.

Adjacent the inner end of the conveyor 50 a pair of posts 55 are mounted on and project upwardly from the side frame members 10 (Figure 60 1) and these posts are connected by a transverse brace 56. Each post 55 carries a bearing 57 at its upper end and the inner end of the conveyor section 50 is supported by a horizontal transverse shaft 58 mounted in the bearings 57. It will be 65 apparent that the shafts 28 and 58 which support the section 20 and conveyor 50 are arranged adjacent each other and accordingly the adjacent rollers of the section 20 and conveyor 50 remain at approximately the same horizontal position 70 under all conditions.

A pair of short channel sections 59 (Figures 1 and 4) are arranged on and secured to the frame members 10 at the end thereof remote from the support 15. These channel members support a 75

transverse member 60 of channel or any suitable cross section and provided with bearing blocks 61. Bearing members 62 are arranged above the transverse member 60 and are provided with depending stems 63 vertically slideable in the blocks 61 and provided with cushioning springs 64. A transverse shaft 65 is journaled in the bearing members 62 and is provided adjacent opposite ends with cams 66 having high and low points 67 and 68 engageable beneath the lower flanges of the side rails 51. A crank handle 69 is carried by one end of the shaft 65.

The operation of the apparatus is as follows:

As previously stated, the present apparatus, as distinguished from my prior construction referred to, is adapted to receive an article, such as a coil of strip steel on the section 20, and these turn the support 15 and place the coil on the section 21 to be discharged therefrom, or it may receive a coil in horizontal position on the section 21 when the latter is in horizontal position, whereupon the support may be turned to the position shown in Figure 1 to support the coil on and discharge it from the section 20. Assuming that a coil is to be received on the section 20 to be discharged from the section 21, the coil will be placed in position on the conveyor 50. When the apparatus is being so employed, each of the cranks 37 and 69 will be rotated 180 degrees from the position shown in Figure 1 whereby the free end of the section 20 will be supported on the low points 36 of the cams 34 while the free end of the conveyor 50 will be supported upon the high points 67 of the cams 66. Accordingly both the section 20 and conveyor 50 will be inclined downwardly toward the right as viewed in Figure 1, the tops of the conveyor rolls 26 and 53 lying in a common inclined plane.

In the particular type of installation for which the present apparatus is especially intended, it is the common practice to handle the coils by magnetic cranes and the coils are sometimes rather roughly placed in position with accompanying shocks to the parts. With the present construction it will be apparent that the free end of the conveyor 50 is supported by the cushioning springs 64 and when a coil is placed on the rollers of the conveyor 50, the shock incident to the placing of the coil is absorbed by the springs 64, thus protecting any of the parts from injury.

In the particular case being considered the coil is placed in position on the rollers 53 in a vertical position, and it readily may be rolled over the rollers 53 and then over the rollers 27 to a position in contact with the rollers 38 of the section 21. The curved side of the coil will lie against the rollers 38 and, as stated, these rollers form a troughed conveyor for the particular purpose of handling substantially cylindrical articles such as sheet metal coils.

With the coil supported on the rollers 27 and lying against the rollers 38, the motor 44 is started and the gear 49 (Figure 5) will be driven through the reduction gearing. The gear 49 meshes with the segment gear 43, and accordingly the support 15 will be turned to the dotted line position shown in Figure 1 with the section 20 approximately in vertical position and the section 21 approximately in horizontal position. If desired, in order to assist in discharging the article from the section 21, the latter may be turned slightly beyond a horizontal position to be inclined downwardly and outwardly with respect to the support 15. The coil will lie on its side on the rollers 38, and

may be moved along the rollers to be discharged from the section 21.

When it is desired to reverse the previously described operation of the apparatus the parts are moved to the dotted line position shown in Figure 5 with the section 21 arranged horizontally or slightly above the horizontal to incline the rollers 38 downwardly and inwardly. The section 21 is then ready to receive a coil which ordinarily is placed thereon by means of a ram truck, the coil 10 lying on its side in horizontal position. The coil is moved over the rollers 38 until the end of the coil contacts the rollers 27, whereupon the motor 44 may be operated to turn the support in a counter-clockwise direction to the solid line position shown in Figure 1.

Under the conditions referred to the section 20 becomes the discharging section of the support, under which conditions it is desired to slope the section 20 and also the conveyor 50 downwardly and outwardly with respect to the support 15. Under such conditions the cranks 37 and 69 will be turned to the positions shown in Figure 1. Therefore, the section 20 will be supported on the high points of the cams 34 while the conveyor 51 will be supported on the low points of the cams 66. With the parts so arranged, the tops of the rollers 27 and 53 will lie in a common plane sloping slightly downwardly and outwardly with respect to the support 15. Accordingly the 30 coil will stand on end on the rollers of the section 20 and the inclination of these rollers and the rollers of the conveyor 50 will facilitate the movement of the coil from the support for delivery as may be desired.

As previously stated, the shafts 28 and 58 are arranged relatively close together to support the remote ends of the section 20 and conveyor 50 for vertical movement when the support 15 is in the position shown in Figure 1. Whether the 40 section 20 and conveyor 50 slope downwardly and outwardly with respect to the section 15 or downwardly and inwardly with respect to the section 15, the tops of the rollers 27 and 53 in either case will lie approximately in the same 45 horizontal plane and therefore will form, in effect, a single continuous conveyor which may be used either for feeding articles to the apparatus or for discharging articles therefrom. It will be apparent that the use of the conveyor 50 with 50 its cushioning means saves the section 20 from substantial shocks incident to the placing of coils in position by overhead cranes or the like. Accordingly the apparatus is highly efficient for handling strip steel coils in either direction, depending upon the destination and the desired position of the coil. It also will be apparent that the apparatus is relatively simple in construction and is effectively protected against injury from shocks incident to the placing in position of very 60 heavy objects such as the coils referred to.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. An article handling apparatus comprising a 70 pair of sections arranged approximately at right angles to each other, means for bodily turning said sections to turn an article and to transfer the article from one section to the other, means for pivotally supporting one section on a hori- 75

5. A horizontal axis, and means for turning said section on said axis to cause such section to assume either of two positions sloping upwardly or downwardly away from the other section when said other section is in vertical position.
6. An article handling apparatus comprising a pair of sections arranged approximately at right angles to each other, means for bodily turning said sections to turn an article and to transfer the article from one section to the other, means for pivotally supporting one section on a horizontal axis, a horizontal shaft spaced from said axis, and a cam carried by said shaft and having high and low points selectively engageable with said last mentioned section to cause it to tilt to either of two positions inclined upwardly or downwardly away from the other section when the latter is in vertical position.
7. An article handling apparatus comprising a pair of sections arranged approximately at right angles to each other and mounted to turn about a horizontal axis parallel to their line of intersection to turn an article and to transfer it from one section to the other, means for pivotally supporting one of said sections for turning movement with respect to a horizontal axis parallel to said line of intersection and located adjacent the end of the pivoted section remote from said line of intersection, a horizontal shaft beneath said pivoted section adjacent the inner end thereof, a cam on said shaft engaging said pivoted section to turn it on its axis to incline it upwardly or downwardly away from the other section when the latter is in approximately vertical position, and a conveyor section arranged in end to end relation with said pivoted section and pivoted on a horizontal axis at the end adjacent said pivoted section to assume positions forming a continuation thereof in approximately a common plane therewith.
8. An article handling apparatus comprising a pair of sections arranged approximately at right angles to each other and mounted to turn about a horizontal axis parallel to their line of intersection to turn an article and to transfer it from one section to the other, means for pivotally supporting one of said sections for turning movement with respect to a horizontal axis parallel to said line of intersection and located adjacent the end of the pivoted section remote from said line of intersection, a horizontal shaft beneath said pivoted section adjacent the inner end thereof, a cam on said shaft engaging said pivoted section to turn it on its axis to incline it upwardly or downwardly away from the other section when the latter is in approximately vertical position, a conveyor section arranged in end to end relation with said pivoted section and pivoted on a horizontal axis at the end adjacent said pivoted section to assume positions forming a continuation thereof in approximately a common plane therewith, a horizontal shaft adjacent the outer end of said conveyor section, and a cam carried by said last named shaft constructed and arranged to tilt said conveyor section to either of two positions coinciding with the tilted position of said pivoted section.
9. An article handling apparatus comprising a support formed of a pair of sections arranged approximately at right angles to each other, means for bodily turning said sections to turn an article and to transfer it from one section to the other, means pivotally supporting one section on a horizontal axis adjacent the end of such section remote from the other section, a conveyor section arranged in end to end relation with and pivoted adjacent said pivoted section when said support is in a predetermined position, and co-related cams engaging the remote ends of said pivoted section and said conveyor section to cause them to assume substantially corresponding angles to the horizontal to form substantial continuations of each other.
